CLAIM

The ornamental design for a container, as shown and described.

DESCRIPTION

FIG. 1 is a top, front, right side perspective view of a container.

FIG. 2 is a bottom, rear, left side perspective view of the container of FIG. 1.

FIG. 3 is a front elevation view of the container of FIG. 1, the rear elevation view being substantially the same.

FIG. 4 is a left side elevation view of the container of FIG. 1, the right side elevation view being substantially the same.

FIG. 5 is a top plan view of the container of FIG. 1.

FIG. 6 is a bottom plan view of the container of FIG. 1.

FIG. 7 is a cross-section view taken along line 7-7 of FIG. 4.

FIG. 8 is a top, front, right side exploded perspective view of the container of FIG. 1.

FIG. 9 is a bottom, rear, left side exploded perspective view of the container of FIG. 1.

FIG. 10 is a top plan view of the base of the container taken along line 10-10 in FIG. 8; and,

FIG. 11 is a bottom plan view of the lid taken along line 11-11 in FIG. 9.

The broken lines in FIGS. 8 and 9 showing an outline of a torque converter are included for the purpose of illustrating environment and forms no part of the claimed design.

1 Claim, 10 Drawing Sheets
